WEB SPLICING DEVICE

Walter C. George, St. Louis, Mo., assignor, by
means assignments, to Gaylord Container Cor-
poration, St. Louis, Mo., a corporation of
Maryland

Original application May 22, 1935, Serial No.
22,789. Divided and this application October
16, 1936, Serial No. 105,942

5 Claims. (Cl. 271—2.1)

My invention relates to a web splicing device and this application is a division of application Serial No. 22,789 filed by me on May 22, 1935 for Roll handling mechanism, now Patent No. 5 2,075,192, March 30, 1937.

The present invention relates to a device located between means for supporting rolls of paper and a machine, such as a corrugating machine, by which the web of paper from the rolls 10 is utilized.

One object of my invention is to provide means for splicing the end of the web of one roll to that of another, thus rendering the operation involving the use of the web substantially continuous.

Another object of my invention is to so construct the splicing mechanism as to provide compensating means for securing true running of the sheet or web which might otherwise be interfered 10 with by inequalities of the roll.

A further object of my invention is to provide the splicing device with tension regulating means for the web.

In the accompanying drawings, which illustrate 5 one form of web splicing mechanism made in accordance with my invention, Figure 1 is an end view, the brake and sprocket drive being omitted; Figure 2 is a top plan view; Figure 3 is a section taken on the line 3—3 of Figure 2; Figure 4 is an enlarged detail view, partly in section and partly in elevation, showing the spring adjustments; and Figure 5 is an enlarged section taken on the line 5—5 of Figure 1.

The mechanism comprises a pair of similar 5 side frames 6 and 7 connected by a tie rod 8. Slidingly mounted in each of the side frames is a bearing block 9 in which is journaled the shaft 10 of the main roll 11. Each frame has 10 slidingly mounted in it at each side of block 9 a bearing block 12 in which are journaled the shafts 13 of the side rolls 14. Roll 11 is provided at the end adjacent frame 6 with a gear wheel 15. This wheel meshes with gear wheels 16 on rolls 14 so that the three rolls are positively 15 driven at the same peripheral speed.

The bearing blocks 12 are biased toward the main roll by coil springs 17, the ends of which extend into sleeves 18 having threaded engagement with the frame and provided with hand wheels 19 by means of which they may be rotated to vary the tension of the springs. After adjustment of the spring tension, the sleeves are secured against rotation by lock nuts 20 actuated 20 by means of handwheels 21.

The shaft 10 of the main roll extends beyond frame 6 and is provided with a sprocket wheel 22 connected by sprocket chain 23 with a sprocket wheel 24 on the outer end of a stud 25. This stud is journaled in a bracket 26 and has mounted 5 on its inner end a bevel gear wheel 27. A driving shaft 28, having its inner end mounted in a bearing 29, is provided with a sliding bevel gear 30. Gear 30 is splined to the shaft so that they must rotate in unison but longitudinal movement 10 of the gear is permitted. Formed in the hub of gear 30 is an annular groove 31 engaging with a pin 32 carried on an arm 33. The arm is mounted on a rock shaft 34 journaled in a bracket 35. A treadle 36 carried on the outer end of the rock shaft is normally held in raised position by a coil spring 37 interposed between the treadle and a bracket 38. While the treadle is held in raised position by the spring, bevel gear 30 will be held out of mesh with wheel 27 so that the 15 rolls will either remain idle or be driven by the friction of the web passing between them. When, however, the treadle is depressed, gear 30 will be moved into engagement with gear 27 so that the 20 rolls will be positively driven from shaft 28 which 25 is supplied with power from any suitable source (not shown).

It is desirable that the tension of the web be maintained constant as it passes to the machine utilizing the said web. While a uniform retarding effect may be imparted to the paper rolls by suitable braking mechanism on the roll supporting means, the tension of the web itself will vary due to the changing diameter of the roll as it unwinds. I, therefore, provide the rolls of my splicer with braking means, supplementary to that of the paper roll support, for securing such uniform tension. Any desired form of retarding device may be employed but I prefer to use the friction brake shown. The end of shaft 10 is provided with a drum 39 forming the inner part of the brake. The outer part comprises two semi-annular members 40 and 41 surrounding the drum. The parts 40 and 41 are pivoted together at 42. At the opposite side of the brake a threaded rod 43 is pivotally attached to part 41 and after passing through a slot in part 40 is engaged by an internally threaded handwheel 44 by means of which the parts 40 and 41 are adjusted toward or from each other to vary the retarding action of the brake. The outer part of the brake is prevented from rotating by a pin 45 carried by frame 6 and engaging lugs 46 on part 41. 45

The operation of my device is briefly as follows: When the end of the web of paper from one roll is reached, a second roll is brought into position by any suitable means, such, for example, as that described in my above mentioned application. The leading end of the new web is brought up to roll 15, pasted and applied to the rear end of the first web. As the superimposed webs pass between the rolls they will be pressed together, thus setting the paste. To take the strain off the pasted splice, the brake is released by means of handwheel 44 and treadle 36 is depressed to positively drive the pasting rolls at the same surface speed as the machine being supplied with paper. As soon as the splice enters the machine utilizing the web, the treadle is released. During the operation of the machine the web may tend to run untrue due to inequalities of the paper roll or other reasons. This tendency may be counteracted by varying the tension of one or more of springs 17 through the action of the hand-wheels 19. This will move the sliding bearings 9 and 12 to slightly cant the rolls in the proper direction to correct the untrue running.

Having fully described my invention, what I claim as new and desire to secure by Letters Patent of the United States is:

1. A splicing device comprising a plurality of rolls, sliding bearings in which said rolls are mounted, springs controlling the pressure between said rolls, said rolls being connected by gearing, a brake for retarding said rolls, means for varying the tension of said springs, driving mechanism for said rolls, and a clutch device for throwing said driving mechanism into and out of operation.
2. A splicing device for webs comprising a frame, a main roll, main bearings slidably mounted in said frame in which bearings the main roll is mounted, a pair of side rolls between which and the main roll the web passes, side bearings slidably mounted in the frame in which bearings the side rolls are mounted, all of said bearings being movable in a direction transverse to the path of the web between the main and side

rolls, and means for biasing each of the side bearings toward the main bearings, said means being independently adjustable, whereby all the rolls may be simultaneously canted to correct untrue running of the web.

3. A splicing device for webs comprising a frame, a main roll, main bearings slidably mounted in said frame in which bearings the main roll is mounted, a pair of side rolls between which and the main roll the web passes, side bearings slidably mounted in the frame in which bearings the side rolls are mounted, all of said bearings being movable in a direction transverse to the path of the web between the main and side rolls, springs biasing each of said side bearings toward the main bearings, and means for independently varying the tension of said springs to simultaneously cant the rolls to correct untrue running of the web.

4. A splicing device for webs comprising a frame, a main roll, main bearings slidably mounted in said frame in which bearings the main roll is mounted, a pair of side rolls between which and the main roll the web passes, side bearings slidably mounted in the frame in which bearings the side rolls are mounted, all of said bearings being movable in a direction transverse to the path of the web between the main and side rolls, gearing connecting said rolls, a brake device for retarding the rolls, springs biasing each of the side bearings toward the main bearings, and means for independently varying the tension of the springs to simultaneously cant the rolls to correct untrue running of the web.

5. A splicing device for webs comprising a pair of frames, a pair of rolls between which the web is pressed, said rolls being journaled in bearings mounted to slide in said frames and to be capable of limited angular movement therein, and means for controlling said angular movement whereby both rolls may be simultaneously canted in a direction transverse to the path of travel of the web between them to correct untrue running of the web.
